UNITED STATES PATENT OFFICE.

HENDRIK MATHYS LIESE, OF HAMBURG, GERMANY.

APPARATUS FOR THE REGULATION OF THE ADMISSION OF AIR TO FURNACES.

Application filed June 12, 1923 Serial No. 644,934.

To all whom it may concern:

Be it known that I, HENDRIK MATHYS LIESE, a citizen of the Kingdom of the Netherlands, residing at Hamburg, Germany, have invented certain new and useful Improvements in Apparatus for the Regulation of the Admission of Air to Furnaces; and I do hereby declare the following to be a full, clear, and exact description of the invention, such as will enable others skilled in the art to which it appertains to make and use the same:

The apparatus employed at the present time for regulating the admission of air to furnaces in correspondence with the grate resistance are actuated by the pressure below the grate, above the grate or in the flues. Since with natural draught the pressure below the grate is subject to but slight variations it is only possible to work from the pressure prevailing above the grate in the flues or in the uptake. This pressure is not dependent exclusively on the grate resistance but on various other factors, as for example on the evolution of gas and on the more or less dirty condition of the flues. It is therefore not possible by the means of known regulating apparatus to admit to the grate the quantity of air most favourable for combustion. In furnaces with forced draught the regulation of the quantity of air has been worked from the pressure prevailing below the grate. But in this case too a satisfactory regulation is not obtainable, since the relationship between the air pressure, the resistance of the grate and the quantity of air passing is unknown. Both methods of working suffer further from the defect that even with correct pressure regulation the quantity of air is dependent on the temperature. The object of the improvements of the regulating device is to provide an apparatus of this class in which the area of the throttling passage is controlled by a turning column of a liquid, which is adapted to assume different levels under the differential pressure of the fluid at the opposite sides of the throttling passage and that this apparatus by means of the rotating liquid is sensitive enough for use in movable vehicles.

In the practical carrying out of this idea a throttling organ is adjusted in accordance with the variable grate resistance by means of a regulating device which depends on a variation in the quantity of air flowing to

the furnaces. The operation of this regulating device is based on the physical law that a quantity of air flowing through a throttling opening or passage suffers a fall of pressure which is dependent on the speed and consequently on the quantity of air passing through. Accordingly if this fall of pressure is transmitted to the regulating device, the latter must adjust the throttling organ which may be a smoke damper, throttle valve, water seal or the like, as soon as there is a sufficient alteration in the quantity of air flowing in. Now by means of this slight fall of pressure it is possible in the known manner, for example by the employment of large pressure surface moved by the fall of pressure, to exercise as great a power as is desired so that the regulating device operates even with the slightest alterations of pressure. The throttling opening may be situated at any desired position in front of the ash pit, a position which is not affected by influence of the temperature under the grate so that the regulation is also independent of the temperature.

In order that the regulation may be used in the same manner with variable steam consumption and consequently with variable air requirements, a control opening is provided, or the fall of pressure in the draught in a conduit is adjustable, in order that the size of the passage opening may be altered in accordance with the steam consumption.

In furnaces devices are at present provided for the increased admission of draught and extra air after the charging of the furnaces with fresh fuel, and this increased admission can be gradually shut off again, but there has hitherto been lack of apparatus which supply air to the fire in correct proportion to the fuel. If, by means of a catalyst for example, more air or extra air is supplied to the coal fire during the gasification period, the present invention is intended to make the duration of the air addition greater with a clinkered fire than with a clear fire in correspondence with the longer gasification period of the coals. In addition there is provided a device by means of which the smoke damper can be closed on opening the fire door.

In order to avoid too tight closing of the smoke damper, there is provided a regulating device for this movement. In a certain position of the smoke damper the energy

effecting its closing movement is gradually balanced, so that the smoke damper comes to a stand-still.

My improved regulating apparatus may 5 be used for various purposes. For the purpose of explaining the invention I shall describe a few examples of using the apparatus. But I wish it to be understood, that 10 my invention is not limited to the examples 10 nor to the constructions of the apparatus shown in the drawings.

In said drawings:

Figure 1 shows an example of construction 15 with furnace fronts in side and front elevation for regulating the combustion air in a stationary installation and in the example chosen the admission of the air is regulated to a determined quantity by the continuous regulation of the smoke damper 20 and a supplementary quantity of air is added during the gasification period.

Figures 2 and 3 show examples of construction 25 for regulation of primary and secondary air with artificial draught on movable vehicles, operated by means of a quantity of rotating liquid, continually fed, the overflow of which serves for operating the organ of regulation.

Figure 1.—The firedoor 1 which opens in 30 the vertical direction carries the extra air door 2 and on the ash pit there is fastened a valve 3 movable by the lever 4. This valve 3 serves to regulate the entry of air. To the ash pit is connected the pipe 7 which 35 transmits the pressure below the grate to the water distributor 8. The water distributor 8 with water supply pipe 32 has two cylindrical overflow vessels, a fixed one 9 and a movable one 10. The overflow vessel 9 is 40 closed towards the exterior by the hood 11. The hood consists of a cover, of which the two concentric vertical walls, dipping into the water between 9 and 10 and into the outflowing water, form an air space, into 45 which projects the pressure transmission pipe 7. The movable overflow vessel 10 has at the bottom a screw-threaded outlet pipe 12 which renders it possible to adjust the relative height of 10 and 11. The water 50 flowing away over 9 passes through the outlet pipe 13 to a receptacle 14. The water flowing away over 10 passes through the outlet pipe 12 to a receptacle 15. The receptacles 14 and 15 actuate the regulation of 55 the smoke damper 20. They are by means of the levers 16 and 17 connected to the axles 18 and 19 and hold each other in equilibrium by means of the eccentric sheaves 21 and 22 and a chain 23. The lever 16 is 60 coupled to the smoke damper 20 by the rod 24.

If the fire door is closed, the water flows 65 from 10 through the pipe 12 to the receptacle 15, thus opening the smoke damper, as soon as the door is opened, the water flows by the

pipe 13 to the receptacle 14 and closes the smoke damper according to the resistance of the grate.

The parts of the apparatus described above are necessary for the regulation of air 70 supply below the grate. Regulating the admission of additional air into the combustion chamber is effected by altering the height of the water level in the receptacle 25, wherein all the water coming from the 75 receptacles 14 and 15 collects and in which is provided the outlet valve 27, which is actuated through a system of levers and rods 28, 29, 30 and 31. The lowering of the 80 water level in the receptacle 25 causes the sinking of the floating body 6, which by the rod 5 opens the additional air supply valve 2. Further due to the lowering of the water level in the receptacle 25 and therefore also in the hood 32^a a communication is established 85 between the hood 32^a and the tube 7 to tube 33 connected to the furnace whereby air is admitted through the hole 34, from the open air.

The valve 3 situated in the ash pit door 90 is brought by means of the lever 4 into a position appropriate to the fuel consumption. The air entering through the openings thus exposed produces a fall of pressure, which through 7 produces a vacuum 95 in the space formed by the hood 11. The vacuum should be maintained in correspondence with the difference in height between the overflow vessels 9 and 10. In this case the water entering 8 through 32 will flow 100 in equal quantity through 13 to 14 and over 9 into 10 thence through 12 to 15. The receptacles 14 and 15 now receive an equal quantity of water; they are in equilibrium and do not move.

If now, owing to the consumption of fuel the draught in the ash pit is increased, correspondingly more water will then also flow away through 13 so that the receptacle 14 will by means of the lever 16 and rod 24 110 close the smoke damper 20. This closing movement continues until the normal condition is again established, that is to say, until the desired vacuum again prevails in the ash pit.

On the formation of clinkers on the grate or with increase of the grate resistance after stoking the reverse takes place and more water flows through 10 to 15 so that by lever 17 and the eccentric sheaves 21, 22 the smoke 120 damper is now raised. By these means not only is the cooling of the fire prevented but there is always a sufficient quantity of air available for the fire.

It is advisable during the stoking to keep 125 the damper closed and this is effected automatically by the fire door 1 operating the lever 29. By these means the damper 20 is immediately closed to prevent the entry of improper air.

As soon as the furnace door is opened, is prevented, which would cool the fire and the vacuum in 7 fades away, so that the damper 20 would open wide. It must, however, be kept closed, in order to prevent the entrance of air while stoking or scouring.

Therefore the furnace-door 1 is connected by means of the rod 28, the lever 29, rod 30 and lever 31 to the receptacle 35 full of liquid, so that opening of the door results in lowering the receptacle 35.

Into this receptacle dips a branch 37 from the pipe 7 and another pipe 36, which in the normal position of receptacle 35 is water sealed by the liquid in 35.

As soon as 35 is lowered, the pipes 7 and 36 are interconnected by 36 and the draught of the chimney secures a vacuum in 7 so that liquid flows away above 9 to receptacle 14, and consequently the smoke damper 20 is closed.

When the fire door is again closed, the smoke damper is automatically adjusted as above described into the position conditioned by the size of the opening of the throttle valve 3, by the other draught conditions and by the altered grate resistance.

The correct adjustment of the smoke damper after stoking is effected more rapidly or more slowly accordingly as the fire is clearer or more clinkered.

In the combustion of coke or the like extra opening of the smoke damper is not at all necessary.

If the fuel contains remarkable quantity of volatile constituents, a sufficient but limited quantity of additional air must be allowed to enter above the grate.

The smoke damper, kept closed while stoking, must open more than normally after stoking, in case of clinkered fire, more than in case of clear fire. Nevertheless, in case of clinkered grate the large opening of the smoke damper must be limited according to the gasifying period of the fuel.

Opening the furnace door causes opening of valve 27, so that receptacle 25 is drained.

Simultaneously hood 32^a is emptied, so that the tubes 33 and 7 are interconnected.

After closing the furnace door the vacuum in the chimney sucks air by the opening 34 in to the combustion chamber.

Simultaneously the pressure in tube 7 is compensated, so that all the liquid flows over 10 to 15 and opens the smoke damper 20.

The more the smoke damper is opened, the more additional air enters by valve 2, so that an economical complete combustion of the developed combustion gases takes place.

The vacuum in the combustion chamber results in increased suction of air by 34, so that the vacuum in 7 and below hood 11 increases and liquid flows away over 9 to receptacle 14, balancing

14 and 15, thus limiting the movement of the smoke damper, and further limiting the vacuum in the ash pit.

By this means the entrance of too much additional air by 2

is prevented, which would cool the fire and destroy the vacuum in 7 and consequently hinder the opening of the smoke damper which is effected earlier or later according to the size of the opening.

The size of 34 70 to the size of the opening. The size of 34 70

may be adjusted according to the percentage of volatile constituents of the fuel.

The duration of the extra opening of the smoke damper is entirely dependent on the condition of the fire in the grate, the

clearer the fire, the greater the vacuum produced in the ash pit, the more water flows away over 10, and the more the fire is clinkered the reverse is the case.

As soon as hood 32^a is filled, the smoke damper is adjusted proportionately to the resistance of the grate or the fuel-bed as described above.

In order to limit the movement of opening of the smoke damper and to avoid too great supply of liquid to

receptacle 14 in case of dressing the grate of one furnace or in boilers with more than one furnace, there is provided in the receptacle 14 a valve 38, which is opened in

a certain changeable position of 14 by rod 39.

In this case 14 is drained by 38 into 15, so that at a certain opening of 38 the receptacles 14 and 15 will be in equilibrium.

Figures 2 and 3. In the case of artificial draught the air flows to the ash pit by the conduit 50, which has a branch 51 to the combustion chamber. The conduit 50 may

be closed by a throttle valve 52, adjustable according to the steam consumption by the lever 97, and has further a valve 53.

Valve 52, lever 97 and valve 53 correspond to valve 3, lever 4 and smoke damper 20 in Fig. 1. Valve 53 is adjusted according to the decrease of pressure before and behind valve 52 and consequently the quantity of air is kept constant according to the position of valve 52. The pressure before valve 52 is transferred by pipe 54 and the pressure behind valve 52 by pipe 55 to the water-distributor 60. This distributor 60, fed continually by a nozzle 66 with liquid, rotating in the distributor, has a cover 61 carrying at its lower side the pipe 62 open below. The bottom of the distributor carries the cylindrical overflow 56, the drain-pipe 58 and the arched overflow 57, covering the wall of the distributor, and carrying a plate 63. This plate is perforated by an air-tube 64 in order to secure atmospherical pressure to the overflow 58. The space between tube 62 and plate 63 is drained by tube 59, concentric to tube 58. The space above the overflow 57 is connected to tube 55 and the space formed by overflow 56 to tube 54. The liquid coming from overflow 56 is conducted by the pipe 58 to receptacle 68 and the liquid from the second overflow 57 is led by the pipe 59 to receptacle 67. These receptacles 67 and 68 regulate the throttle valve 53. The receptacles 67 and 68 are by means of the levers 69 and 70 con-

nected to the axles 71 and 72 and hold each other in equilibrium by means of the eccentric sheaves 73 and 74, and a chain 75. The lever 70 is coupled to the throttle valve 53 by the rod 76.

The parts of the apparatuses described until now are necessary for the regulation of air supply below the grate. As described in Fig. 1 the regulation of the entrance of 10 additional air is operated by altering the height of the water level in the receptacle 80, where all the water coming from the receptacles 67 and 68 is collected. In the receptacle 80 there is provided the outflow valve 15 81, which can be raised through a lever 82 and a chain 83. The lever 82 can be actuated by means of the chain 87, lever 84, which is fastened to the axle 85 of the fire door 86.

20 Sinking of the water level in 80 causes sinking of the floating body 88, which is connected by a wire-rope or chain 90, guided by a roller 89, and the lever 92 to the throttle valve 91 in the conduit 51, so that sinking of 88 results in opening the conduit 51 and vice versa. To the lever 82 are fixed the receptacles 93 and 94. Into these receptacles 93 and 94 terminate the pipes 55 and 94; 94 is connected by pipe 95 30 to the ash pit. Into the tube 96 dips to a certain depth the pipe 54. Just as in Fig. 1 the receptacle 14, valve 38 and rod 39 prevent an excessive opening of the smoke damper, here the valve 77 in the receptacle 35 67 drains 67 in the lowest position thereof, where it is opened by chain 78.

The air is led to the fire by the conduit 50 and suffers a decrease of pressure when 40 passing the throttle valve 52, adjusted according to the consumption of steam. The pressures before and behind the throttle valve 52 are transferred by the pipes 54 and 55 to the spaces above the overflow vessels 56 and 57, within the distributor 60, continually fed by a nozzle 66, which by its special 45 position causes the liquid contents of the distributor to rotate. This rotation is necessary in order to secure sufficient insensibility of the level of liquid against movement of 50 the distributor, so that this apparatus is fit for use in movable vehicles like e. g. ships etc. This difference of pressure is kept constant by the liquid flowing by the pipes 58 and 59 corresponding to the difference 55 of height of the overflows 56 and 57, so that in case of increased resistance of grate more liquid flows away over the overflow 56 to receptacle 68, which by its increased weight 60 opens the throttle valve 53 by means of the lever 70 and rod 76. In the reverse case of clear or burnt out fire liquid flows by pipe 59 from overflow 57 to receptacle 67, so that the lever 69 and the two sheaves 73 and 74 shut the throttle valve 53. In order to 65 secure slow opening or closing of the throttle

valve 53, the sheaves 73 and 74 are eccentric so that the movement of the receptacle being fed by liquid grows smaller and smaller, while that of the empty receptacle, in a similar proportion increases. Thus the 70 necessary quantity of air is supplied to the fire according to the position of the throttle valve 52 adjustable by the lever 97.

In order to avoid the entrance of improper air when opening the fire door, there 75 is suspended from the lever 82 the receptacle 93 full of water, which is lowered when opening the fire door so that the tube 55 dipping into the water is connected to the atmosphere, so that compressed air may 80 escape from 55. Consequently all the liquid fed to the distributor 60 runs by the overflow 57 to the receptacle 67, and the throttle valve 53 begins to close. In order to avoid 85 complete closing of the valve, there is provided to the receptacle 67 the valve 77 which is opened in a certain position of receptacle 67 by chain 78, so that the water may escape to receptacle 68 opening the throttle valve 53.

In order to secure complete combustion in case of fuel with abundant volatile constituents, additional air is supplied. When the fire door 86 is opened, lever 82 is lifted by means of axle 85, lever 84 and chain 87, 90 so that by chain 83 the drain-pipe 81 is lifted and receptacle 80 is drained by the drain valve 98. Consequently the floating body 88 is lowered, opening simultaneously the throttle valve 91 by the wire-rope 90 and lever 92 so that by the pipe 51 a connection is produced between the air conduit 50 and the combustion chamber. As soon as the receptacle 80 is filled, the floating body is 95 lifted, so that the throttle valve 91 is again 100 closed.

In order to adjust the position of valve 91 according to the quantity of volatile constituents of the fuel lever 92 may be lengthened or shortened, so that the movement of 110 the valve 91 may be changed in proportion to that of the floating receptacle 94.

When opening the fire door 86, lever 82 has lifted receptacle 94 full of water so far, that in spite of receptacle 86 being drained 115 the pipe 54 dips into the concentric tube 96. After closing the fire door 86 receptacle 94 is lowered, so that a communication between 95 and the connecting pipe 54 is provided. By this means the pressure in 54 decreases, 120 so that all the liquid flows away over the overflow 56 and the throttle valve 53 is opened. By excessive opening the throttle valve 53 an increased supply of air is effected, so that the difference of pressure between 54 and 55 is increased. If the difference of height between the overflows 56 and 57 is about a quarter of an inch or more, and by connection to the tube 95 about $\frac{1}{8}$ 125 of an inch of pressure is taken away from 130

tube 54, liquid flows away from overflow 57 and closes the throttle valve 53 in case of difference of pressure of $\frac{3}{8}$ of an inch. This difference of pressure takes place the quicker, the more air flows through pipe 50, that is to say, the less pressure is below the grate or less resistance is prevailing in the fuel-bed, and the slower, the less air passes the fuel-bed, that is to say in case of clinkered fire. If the liquid in the receptacle 80 has risen, so far, that pipe 54 dips into the water, the increased supply of air is also stopped, after the gasification of the volatile constituents of the fuel in case of clinkered fire.

The valves 3 and 52 are adjusted by hand according to the quantity and calorific value of the fuel, and can also be actuated by a steam meter, a carbon dioxide recording apparatus or the like.

It is self-evident that for regulating the quantity of air any kind of throttling medium placed in the path of the flow can be used, as also there may be employed any form of receptacle for the outflowing water.

In producer furnaces it is mostly advisable to employ two apparatuses one for the combustion to carbon monoxide and the other to carbon dioxide.

I claim:

1. In an apparatus of the class described, the combination with a furnace of an air conduit for said furnace provided with an opening of known size, a receptacle with two overflow vessels, means for ensuring a constant supply of liquid to said receptacle and means actuated by the liquid overflowing from said receptacle for transferring the pressure in front of and behind the said opening to said receptacle whereby the quantity of air supplied to the furnace is adjusted according to the grate resistance.

2. In an apparatus of the class described, the combination with a furnace of an air conduit for said furnace provided with an opening of known size, a receptacle with two overflow vessels, means for ensuring a constant supply of liquid rotating in said receptacle, and means actuated by the liquid overflowing from said receptacle for transferring the pressure in front of and behind the said opening to said receptacle whereby the quantity of air supplied to the furnace is adjusted according to the grate resistance.

3. In an apparatus of the class described the combination with a furnace and its combustion chamber of an air conduit supplying primary and secondary air to said furnace and provided with an opening of known size, a receptacle with two overflow vessels, means for ensuring a constant supply of liquid rotating in said receptacle, and means actuated by the liquid overflowing from said receptacle for transferring the pressure in the combustion chamber to said receptacle

whereby the quantity of primary and secondary air supplied to the furnace is adjusted according to the grate resistance and the quantity of volatile constituents in the fuel.

4. In an apparatus of the class described the combination with a furnace and its combustion chamber of an air conduit supplying primary and secondary air to said furnace and provided with an opening of known size, a receptacle with two overflow vessels, means for ensuring a constant supply of liquid rotating in said receptacle, and means actuated by the liquid overflowing from said receptacle for transferring the pressure in the combustion chamber to the atmosphere whereby the quantity of primary and secondary air supplied to the furnace is adjusted according to the grate resistance and the quantity of volatile constituents in the fuel.

5. In an apparatus of the class described the combination with a furnace of an air conduit for said furnace provided with an opening of known size, a receptacle with two overflow vessels, means for ensuring a constant supply of liquid to said receptacle and a regulating organ actuated by the liquid overflowing from said receptacle and comprising two receptacles held in equilibrium by two eccentric sheaves and a connecting chain for transferring the pressure in front of and behind said receptacle to said regulating organ whereby the quantity of air supplied to the furnace is adjusted according to the grate resistance.

6. In an apparatus of the class described the combination with a furnace and its grate of an air conduit for said furnace provided with an opening of known size, a receptacle with two overflow vessels, means for ensuring a constant supply of liquid to said receptacle, a pipe transmitting the pressure below the grate to said receptacle, means for diminishing the pressure in said pipe behind said opening while the fire door is open, a regulating organ and means for actuating said regulating organ by the liquid overflowing from said receptacle for transferring the pressure in front of and behind said opening to the said receptacle by said pipe whereby entrance of excess air to the furnace is prevented.

7. In an apparatus of the class described the combination with a furnace and its grate of an air conduit for said furnace provided with an opening of known size, a receptacle with two overflow vessels, means for ensuring a constant supply of liquid to said receptacle, a pipe transmitting the pressure below the grate to said receptacle, means for diminishing the pressure in said pipe in front of said opening when the fire door is closed, a regulating organ and means for actuating said regulating organ by the liq-

uid overflowing from said receptacle for transferring the pressure in front of and behind said opening to the said receptacle by said pipe for ensuring sufficient supply 5 of air necessary for complete combustion of the volatile constituents of the fuel.

8. In an apparatus of the class described the combination with a furnace of an air conduit for said furnace provided with an 10 opening of known size, a receptacle with two overflow vessels, means for ensuring a constant supply of liquid rotating in said receptacle, a regulating organ actuated by the liquid overflowing from said receptacle 15 and comprising two receptacles held in equilibrium by two eccentric sheaves and a connecting chain for transferring the pressure in front of and behind said receptacle and means for preventing the total closing 20 of the air supply to the furnace.

9. In an apparatus of the class described the combination with a furnace of an air conduit for said furnace provided with an

opening of known size, a receptacle with two overflow vessels, means for varying the 25 height of said overflow vessels, means for ensuring a constant supply of liquid to said receptacle and means actuated by the liquid overflowing from said receptacle for transferring pressure to said receptacle whereby 30 the quantity of air supplied to the furnace is adjusted according to the grate resistance.

10. In an apparatus of the class described the combination with a furnace of an air conduit for said furnace provided with an 35 opening of known size, a receptacle with two overflow vessels, means for ensuring a constant supply of liquid to said receptacle and means actuated by the liquid overflowing from said receptacle for transferring pressure to said receptacle whereby the quantity 40 of air supplied to the furnace is adjusted according to the grate resistance.

In testimony whereof I hereunto affix my signature.

HENDRIK MATHYS LIESE.
